FRAME FOR A SEAT OR SIMILAR ARTICLE

Tadao E. Inouye, 5724 Fallsgrove St.,
Los Angeles, Calif. 90016

Filed June 3, 1971, Ser. No. 149,879

Term of patent 14 years

Int. Cl. D6—02

U.S. Cl. D6—191

Fig. 1.

Fig. 2.

FIG. 1 is a front perspective view of a frame for a seat or similar article showing my new design in elongated form for use as a sofa; and

FIG. 2 is a side perspective view of a modified version of the frame of FIG. 1 showing the same in shorter form for use on a chair.

I claim:

The ornamental design for a frame for a seat or similar article, substantially as shown.
